UNITED STATES PATENT OFFICE

127,611

DESIGN FOR A MEASURING SPOON

William A. Hadfield, Upper Darby, Pa., assignor
to Pennsylvania Salt Manufacturing Company,
Philadelphia, Pa.

Application February 4, 1941, Serial No. 98,717

Term of patent 14 years

To all whom it may concern:

Be it known that I, William A. Hadfield, a citizen of the United States, residing at Upper Darby, county of Delaware, and State of Pennsylvania, have invented a new, original, and ornamental Design for a Measuring Spoon, of which the following is a specification, reference being had to the accompanying drawing, forming part thereof.

Fig. 1 is a perspective view of a measuring spoon showing my new design;

Fig. 2 is a side elevational view; and
Fig. 3 is a top plan view.

I claim:

The ornamental design for a measuring spoon, substantially as shown.

WILLIAM A. HADFIELD.
